CHANGEABLE ADVERTISING DEVICE, INCLUDING ADJACENT ENDLESS BELTS MOVABLE IN OPPOSITE DIRECTIONS

Adolph Erisman, Port Richmond, N. Y.

Application December 29, 1945, Serial No. 638,321

10 Claims. (Cl. 40—32)

1

This invention relates to a changeable advertising device and has for its general object and purpose to provide an advertising display sign of novel construction which may be manufactured in highly attractive form at comparatively small cost and in which the advertisement is displayed in such manner as to arouse the curiosity and focus the attention of passers by.

It is a more particular object of the invention to provide an advertising display sign embodying means for alternately displaying different advertisements at opposite sides of the sign.

Another object of the invention resides in the provision of a plurality of endless belts having exposed surfaces disposed in a common plane and upon which parts of the advertisements displayed at opposite sides of the sign are painted or otherwise delineated, together with means for moving adjacent belts in relatively opposite directions to first disarrange or scramble the parts of the letters or other advertisement displayed at one side of the sign, and then bring the same together in accurate registration at the opposite side of the sign.

A further object of the invention is to provide improved means for operatively mounting the belts and the actuating mechanism therefor in an elongated housing structure, said operating mechanism including means providing a dwell period of the required length between periodic operations of the belts, during which the advertisement may be read.

It is an additional object of the invention to provide a housing structure embodying top and bottom sections together with means rigidly connecting said sections in assembled relation which also serves to guide the belts and prevent relative transverse displacement of their advertisement carrying surfaces.

My invention also comprehends an advertising display device as above characterized the several cooperating parts of which are of simple and durable structural form, and which may be continuously operated at negligible expense.

With the above and other subordinate objects in view, the invention comprises the improved changeable display device and the form construction and relative arrangement of its several parts, as will hereinafter be more fully described, illustrated in the accompanying drawings and subsequently incorporated in the subjoined claims.

In the drawings, wherein I have disclosed one simple and practical embodiment of the invention and in which similar reference characters

2

designate corresponding parts throughout the several views:

Figure 1 is a perspective view illustrating one desirable ornamental embodiment of the present invention;

Figure 2 is a vertical longitudinal sectional view;

Figure 3 is a horizontal section taken substantially on the line 3—3 of Figure 2;

10 Figure 4 is a horizontal section taken substantially on the line 4—4 of Figure 2; and

Figure 5 is a vertical transverse section taken substantially on the line 5—5 of Figure 2.

Referring in further detail to the drawings, in 15 the selected embodiment of my invention, the display apparatus and the operating mechanism therefor is mounted as a separately assembled unit within and between narrow elongated top and bottom housing sections 10 and 12 respectively. This unit assembly includes upper and lower frame plates 14 and 16 respectively which are rigidly connected in vertically spaced apart relation at their opposite ends by the rods 18. The end portions of the lower frame plate 16 are 20 upwardly offset as at 20 and extend in parallel relation to the corresponding ends of the upper frame plate 14. In these end portions of the two frame plates vertical shafts 22 and 24 respectively are journaled. A plurality of pulleys, six in 25 the present instance, are mounted upon each of these shafts, alternate pulleys 26 being fixed to the shaft by means of set screws 28 for unitary rotation therewith, while the remaining pulleys 30 are loose on the shaft. It will be noted from 30 reference to Figure 2 that the fixed pulleys on one of the shafts 22—24 are in horizontal alignment with the loose pulleys on the other shaft.

The pulleys 26 and 30 are peripherally formed 35 to receive the V-shaped belts 32. The opposite side walls of the belt receiving grooves in the fixed pulleys 26 are connected by the drive pins 34 which are received between space teeth or ribs 36 formed upon the inner sides of the respective belts, as shown more particularly in Figure 3 of 40 the drawings.

Above the frame plate 14, a gear member 38 is 45 fixed upon the upper end of the shaft 22. This gear is in constant mesh with a similar gear 40 journaled upon a stud shaft 42 fixed in the frame plate 14, and with this gear, a relatively small diameter sprocket 44 is integrally formed. To the upper end of shaft 24, a similar sprocket 46 is fixed. These sprockets are connected by the endless chain 48 engaged by the relatively large 50 diameter drive sprocket 50 fixed to the upper end

of the vertical shaft 52 journalled in the frame plates 14 and 16.

To the under side of the frame plate 14, the flange 56 of a fractional horse-power gear reduction motor 54 is secured by rivets 58. In a suitable bearing 60 on the motor case a vertically disposed shaft 62 is journalled and has a beveled pinion 64 at its upper end in mesh with the beveled pinion 66 on the drive shaft of the motor. To the lower end of shaft 62, crank arm 68 is fixed and is pivotally connected at 72 with one end of the connecting rod 70. The other end of this rod is provided with a longitudinal slot 74 in which a pin 78 fixed in the crank arm 76 on the lower end of shaft 52 is slidably engaged.

The outer surfaces of the side walls of the housing sections 10 and 12 are provided with longitudinally continuous shallow grooves or channels 80. Before assembly of the above described mechanism with the housing sections the lower angularly offset edge portions 84 of the belt guiding plates 82 are secured to the inner side faces of the opposite side walls of the lower housing section 12 by screws 86, the heads of which are flush with the base wall of the channel 80. The assembled mechanism is now mounted upon and secured to the lower housing section 12 by the screws 88 disposed through registering openings in the bottom wall of said housing section and frame plate 16 and threaded into tapped bores in the lower ends of rods 18.

The upper angularly offset ends 90 of the guide plates 82 extend above the frame plate 14 and are secured to the inner faces of the opposite side walls of housing section 10 by screws 92 having their heads flush with the base walls of the channel 80. The housing sections 10 and 12 are preferably of wood and after the assembly is completed, the grooves or channels 80 in the housing walls receive the chrome metal strips 94 concealing the screws 86 and 92 and having their outer surfaces flush with the outer surfaces of the housing walls. These walls may be painted a desirable color so that the exposed surfaces of the metal strips 94 offer an ornamental color contrast therewith. It will be observed that since the guide plates 82 are located closely adjacent to the inner sides of the belts 32 they will prevent inward displacement of the belts relatively to each other between the spaced series of pulleys and maintain the outer surfaces of said belts substantially in a common plane with the outer surfaces of the side walls of the upper and lower housing sections 10 and 12.

The top wall of housing section 10 is preferably provided centrally thereof with a multiplicity of ventilating apertures 96 for the motor 54, and in the opposite ends thereof eye bolts 98 are suitably secured, whereby the sign may be conveniently hung or suspended from a supporting structure.

While the belts 32 are stationary, suitable advertisements are painted or otherwise delineated upon the exposed surfaces thereof at opposite sides of the sign, a portion of such advertising matter being carried by each of the belts as indicated at 100 in Figure 1 of the drawings. These advertisements may comprise either words, as shown, or descriptive symbols, trade-marks or pictorial representations of a commodity, or various combinations thereof, and it will be understood that the advertisements displayed at opposite sides of the sign when the belts are stationary, are different.

Having above-described the several structural

features of the present invention, the operation thereof will be understood as follows.

Assuming that the belts and the operating mechanism therefor are in the relative positions seen in Figures 1 and 3, and that in the operation of motor 54 crank arm 68 is rotated in a counter-clockwise direction, during the initial portion of such movement, corresponding to the length of the slot 74, the belts remain stationary and the advertisements at opposite sides of the sign are legible. At the end of this period connecting rod 70 coacts with pin 78 on crank arm 76 to rotate the shaft 52, thus simultaneously transmitting rotation through the large sprocket 50 and chain 48 and the small sprockets 44 and 46 to the pulley operating shafts 22 and 24. The adjacent belts are thus driven by pins 34 on the two series of fixed pulleys 30 in relatively opposite directions and at the same speed. The adjacent portions of the advertising matter 100 on the belts will therefore be relatively displaced, resulting in such scrambling or jumbling of the parts of the advertisement that it is no longer intelligible. The ratio of the small sprockets 44 and 46 relative to the large sprocket 50 is such that in the rotation of the latter through approximately one hundred and eighty degrees the belts will be moved for a distance which is substantially equal to one half of the length of the housing, at which time the parts of the advertisements carried by said belts will again be disposed in exact registration, but with the advertisements reversed with respect to the opposite sides of the housing from the preceding display. In the continued rotation of crank 68, connecting bar 70 will be moved relative to pin 78 for the length of slot 74 during which time the belts remain stationary, after which the connecting rod 70 again engages pin 78 to rotate shaft 52 in a clockwise direction, reversing the direction of movement of the adjacent belts and restoring the same to the positions seen in Figure 1. It will thus be understood that in each cycle of operation, the two advertisements carried by the series of belts are displayed at each side of the sign.

From the above, it will be appreciated that by the movement of the adjacent parts of the lettering or other advertising matter in relatively opposite directions lengthwise of the sign, the interest or curiosity of the observer is sufficiently aroused that, approaching the sign at either side thereof, he will linger for the necessary time to read both of the advertisements carried by the moving belts. Of course, it will be apparent that, if desired, the upper housing section 10 may be equipped with means for mounting fluorescent electric tubes or other means to illuminate the exposed surfaces of the belts so that the sign may be effectively used during the night as well as day.

Finally, it will be observed that the individual mechanical elements of an advertising display sign having the several novel features above described, are of simple and durable structural form which may be fabricated at low cost and easily and quickly assembled in proper cooperative relation. It is also to be noted that by reason of the highly compact assembly of the several parts the overall dimensions of the sign are held to a minimum so that it may be mounted and arranged for operation in a relatively restricted space where more elaborate mechanisms, heretofore devised for the same general purpose could not be effectively employed.

The invention may be embodied in other

specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by the United States Letters Patent is:

1. In a changeable display sign, a plurality of parallel vertically superposed endless belts movable in a common plane and each carrying portions of two advertisements, and means operatively connected to positively drive each of said belts and periodically move the adjacent belts at equal speeds in relatively opposite directions and register the portions of the respective advertisements carried thereby alternately at opposite sides of the sign.

2. The changeable display sign defined in claim 1 wherein said means comprises two spaced sets of pulleys, a common supporting shaft for the pulleys in each set, alternate pulleys in each set being loosely mounted on the associated shaft and the remaining pulleys being fixed thereto, and corresponding in axial location with the fixed and loose pulleys respectively in the other set, said belts being respectively engaged with the corresponding fixed and loose pulleys, and said driving means including motor driven means for reversibly rotating said shafts in relatively opposite directions.

3. In a changeable display sign, a plurality of parallel vertically superposed endless belts of equal length each carrying portions of two advertisements and having their exposed surfaces disposed in a common plane at opposite sides of the sign, an operating motor, a shaft driven thereby, and means operable in each revolution of said shaft to reversibly move the adjacent belts at the same speeds in relatively opposite directions and register the portions of the respective advertisements carried thereby alternately at opposite sides of the sign.

4. The changeable display sign as defined in claim 3 wherein said means includes a lost motion connection to provide a dwell period following each registration of the advertisement portions, and thereafter cause a reversal in the direction of relative movement of the adjacent belts.

5. In a changeable display sign, a supporting frame, spaced vertical shafts journaled in said frame, a series of belt pulleys on each of said shafts, means securing alternate pulleys in each set in fixed relation to the shaft for rotation therewith, the remaining pulleys in each set being loose on the shaft and located axially thereof correspondingly to fixed pulleys on the other shaft, belts engaged with the corresponding fixed and loose pulleys each carrying portions of two advertisements, means on the fixed pulleys coacting with means on the respective belts to positively move the latter, an operating motor, a shaft driven thereby, and means operatively connecting said motor driven shaft with said vertical shafts to reversibly rotate the latter in relatively opposite directions and periodically move the adjacent belts in relatively opposite directions to

register the portions of the respective advertisements carried thereby alternately at opposite sides of the sign.

6. The changeable display sign as defined in claim 5 in which said last-named means includes a shaft mounted in the frame, a sprocket fixed to one end thereof, a sprocket fixed to one of said vertical shafts, a gear fixed to the other of said vertical shafts, a gear rotatably mounted on the frame and meshing with said first-named gear, a sprocket integral with the second-named gear, a drive chain driven by said first-named sprocket and trained about the gear sprocket and the sprocket on said vertical shaft, and a lost motion operating connection between said motor driven shaft and the shaft of said first-named sprocket providing a dwell period in the movement of the belts after each registration of the advertisement portions carried thereby.

7. An advertising display sign comprising upper and lower housing sections, a display unit assembly including advertisement carrying members mounted for movement relative to each other and said housing sections, and rigid connecting elements secured to corresponding side walls of the housing sections and extending between the sections closely adjacent to said movable members to prevent angular displacement thereof from their paths of movement.

8. An advertising display sign comprising upper and lower housing sections, a display unit assembly including a plurality of relatively movable endless belts having advertisement carrying surfaces, means for rigidly mounting said unit assembly within the lower housing section, and belt guiding means carried by the opposite side walls of said housing sections and disposed closely adjacent to the belts to prevent lateral inward displacement thereof from a plane which is substantially coincident with the side walls of the housing sections.

9. The advertising display sign as defined in claim 8 wherein said belt guiding means comprises rigid metal plates internally secured to corresponding side walls of the housing sections and constituting the sole means supporting the upper housing section with relation to the display unit.

10. The changeable display sign defined in claim 1 wherein the belt operating means includes separate drive shafts for the adjacent belts, and means operatively connected with said shafts to rotate the same in opposite directions and to periodically reverse the direction of relative rotation of said shafts.
